(57) **CLAIM**

The ornamental design for a water dispensing device, as shown and described.

DESCRIPTION

FIG. 1 is a front perspective view from top and right side of a water dispensing device showing our new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines are directed to environment and are for illustrative purposes only; the broken lines form no part of the claimed design.
